DESIGN FOR AN AUTOGRAPHIC REGISTER

Louis Jensen, Chicago, Ill., assignor to United Autographic Register Co., Chicago, Ill., a corporation of Illinois

Application March 26, 1934, Serial No. 51,194

Term of patent 3½ years

To all whom it may concern:

Be it known, that I, LOUIS JENSEN, a citizen of the United States, residing at Chicago, in the county of Cook and State of Illinois, have invented a new, original and ornamental Design for an Autographic Register, of which the following is a specification, reference being had to the accompanying drawing forming a part thereof, in which:

The figure is a perspective view of an autographic register, showing my design.

I claim:

The ornamental design for an autographic register, substantially as shown.

LOUIS JENSEN.
